UNITED STATES PATENT OFFICE

GEORGE R. LAWRENCE, OF CHICAGO, ILLINOIS

ENGINE

Application filed January 23, 1928. Serial No. 248,837.

This invention relates to improvements in internal combustion engines, more particularly to two stroke cycle, scavenging gas engines for high speeds. The main objects of this invention are to provide a two stroke cycle gas engine capable of such piston speeds as four to six hundred feet per minute in order to obtain extreme lightness and high efficiency; to provide means for supplying a measured amount of fuel to each cylinder; to provide for an even and steady distribution of the fuel to the several cylinders; and to provide a simple and reliable fuel supply mechanism which is capable of being operated at high rates of speed.

In the accompanying drawings is illustrated a gas engine embodying my invention, in which:

Fig. 1 is a fragmentary side elevation of the upper portion of the engine, showing the fuel supply mechanism for a four cylinder, two cycle, scavenging engine, having approximately a two and three-eighths inch bore and a three and three-quarter inch stroke.

Fig. 2 is a plan view of the parts shown in Fig. 1, with parts broken away and parts shown in section.

Fig. 3 is a transverse section taken on line 3—3 of Fig. 1.

Fig. 4 is taken on line 4—4 of Fig. 2.

Fig. 5 is taken substantially on line 5—5 of Fig. 2.

Fig. 6 is a section of the lower portion of the mixer, taken on line 6—6 of Fig. 2.

Fig. 7 is a timing diagram.

The engine shown in the drawings operates on the two cycle, scavenging principle, and a substantially pure fuel vapor is injected into the cylinders instead of liquid fuel. In other scavenging engines used heretofore, a measured amount of air was blown through the cylinder as the cylinder wall exhaust ports were uncovered; then a measured amount of mixture was blown in before the ports were closed. To obtain any but extremely slow speeds the amount of scavenging air was necessarily limited because the scavenging air and the mixture had to both be blown in during the period the exhaust ports were open. Usually the scavenging air was measured to be approximately 70% of the volume of the cylinder. This, of course, indicates that the burnt charge was merely diluted instead of completely cleaned out. Such engines have been built in very large sizes, and have a long connection from the fuel and air pumps to the cylinders. Other engines such as the Diesel type oil burning engines injected the oil into the cylinders at the beginning of the power stroke with a pressure of about one thousand pounds on the oil and with a compression of between four and five hundred pounds in the cylinder, to obtain a slow burning, some of the burnt charge being purposely left in the cylinder to deaden the combustion.

In the present engine, several cylinder volumes of air are blown straight through the cylinder from the top, out through the exhaust ports to thoroughly clean and also to cool the cylinder. Then a measured amount of the fuel vapor is forced into the cylinder during the first half of the compression stroke. This allows more time for both the scavenging and the fuel injection; that is, these operations take place in a larger angle of crank shaft rotation. Accordingly, since the fuel requires an appreciable amount of time to flow through the passages, the pistons may be operated at higher speeds than where less angularity is provided, and higher efficiencies obtained.

By more thoroughly cooling the inside of the cylinders and the piston heads, the danger of flare-backs is eliminated, and air cooling throughout becomes feasible. By injecting the fuel during the first part of the compression stroke, only a low pressure is required on the fuel. This decreases the amount of power used for handling the fuel, and permits lighter pumping mechanism. Also, in the present invention, the pumps are very close to the cylinders. This shortens the passages and also increases the efficiency of the pumps and greatly reduces their size.

Another distinguishing characteristic of this invention is the manner in which one pump is made to serve for two cylinders without requiring mechanically operated valves. In a four cylinder engine, incorporating the

present invention, the cylinders are arranged to fire in a one-three-two-four, or a one-four-two-three order so that the end cylinders are each adjacent to a cylinder being functioned in opposite phase relation. Two fuel pumps drawing air through a fuel vapor reservoir are used, one for the first and second cylinders and the other for the second and third. Then, since the cycle is completed in two strokes of the piston, the piston in one cylinder of each pair is coming up on the compression stroke while the other is going down on the combustion or expansion stroke.

The pumps are of the piston type and are driven from a shaft rotated at twice the number of revolutions of the engine crank shaft, and serve first one cylinder and then the other. Each pump has two outlet connections, one to each cylinder of the corresponding pair, and each connection has a return check valve therein. As a result, the explosion pressure closes the check valve for that cylinder and the expulsion stroke of the fuel pump opens the other check valve and forces the fuel into the cylinder which is undergoing compression.

Referring to the drawings, the reservoir 1 and the fuel pumps 2 are mounted at one side of the engine cylinders 3. Each pump is connected by a suction tube 4 into the reservoir 1, and is provided with a piston 5, connected to the double-time shaft 6. The shaft 6 is rotatably mounted in brackets 7, bolted to the side of the hollow cam shaft housing 35 or engine head 8, and is geared in a two to one speed ratio to the cam shaft 9, which, in a two cycle engine, rotates at crank shaft speed.

The time shaft 9 is connected for driving to the engine crank shaft, not shown, to the crank pins of which the pistons 10 are connected by means of the connecting rods 11, in such manner that the shaft 9 rotates in synchronism with the crank shaft. The upper ends of the cylinders 3 are each connected into the head 8 by flanged rings 12 which thread into the upper ends of the cylinders with the flanges gripping the upper surface of the plate 13 which is bolted to the bottom of the head 8, forming a closed air space in the head. One large air valve 14 is provided in the upper end of each cylinder, seated on the end of the ring 12 and having the stem 15 slidably mounted in the bearing 16 which is formed in the bridge 17 across the ring 12. The valve spring 18 seats against the bridge 17 and bears against the spring cup 19, which is attached to the upper portion of the valve stem.

A finger 20, pivotally mounted in the side wall of the head 8, is inserted between the upper end of the valve stem 15 and the valve operating cam 21 which is an integral part of the shaft 9. In the position shown in Fig. 3 the piston is just starting the down-stroke,

or expansion stroke, the gas having been compressed on the up-stroke of the piston and fired by a spark plug 22, mounted in the spark plug boss 122. The spark plug may be of any form commonly used, and is fired by any suitable ignition device. The cam shaft 9 is rotating clockwise, and it will be seen that the air valve 14 has been closed during the up-stroke of the piston. Near the bottom of the stroke, the piston uncovers the open exhaust ports 23, allowing the burnt gas to escape, and the air valve 14 is opened by the cam 21, as indicated in dotted lines in Fig. 3.

Air under pressure is supplied to the chamber in the head 8 in any suitable manner, as by an air compressor driven by the engine, so that several volumes of air are blown through the cylinder before the piston again closes the exhaust ports 23 on the return stroke. A measured amount of dense fuel vapor is then forced into the clean air in the cylinder during the earlier part of the compression stroke to form an explosive mixture, and the new charge is then compressed and fired.

A light, spring pressed return check valve 24 is provided in the bottom of the casing 25 of each fuel pump 2, in the opening into the suction pipe 4, see Fig. 4. The outlet from the pump is through a horizontal passage 26, in the bottom of the pump, see Figs. 2 and 4, which connects into a vertical passage 27, in the side wall of the casing 25, through a port 28, which is closed by a ball check valve 29, under pressure of a spring 127. A short distance above the ball check 29, the passage 27 is connected into the two vertical passages 30-30 through short inclined passages 31, shown in dotted lines in Fig. 1. A ball check 32 is provided in each of the passages 30, and the passages communicate through the nipples 33 and tubes 34 into the adjacent cylinders, above the highest position of the piston head. Thus it will be seen that the pump outlet connects into two oppositely functioned cylinders with a return check valve for each cylinder.

When one piston is near the top center and the cylinder is under compression or under the combustion pressure, the corresponding check valve 32 in the connection to the fuel pump is closed. Then, when the pump piston moves down and builds up sufficient pressure the check valve 32 for the opposite cylinder is lifted and the fuel is forced into the proper cylinder.

The fuel vapor reservoir is common to both fuel pumps, and comprises a shell 35 which is clamped between the upper and lower heads 36 and 37 by means of the central perforated pipe 38, which threads into the lower head 37, and into the cap nut 39. The bottom head is provided with passages 40 connecting the pipes 4 to the interior of the center pipe 38; drain passages 41 leading from the bottom of the chamber in the shell

35; and inlet passages 42 leading to the supply pipe 43 which is connected into the lower head 37.

During the up-stroke of the fuel pump 5 pistons 5, the check valves 29 and 32 in the outlet passages are closed, and the check valve 24 is lifted and a partial vacuum is set up in the passages leading to the reservoir, in the reservoir itself, and in the suction pipe 43 which leads from the reservoir down into the liquid in the liquid fuel receptacle 44. The receptacle 44 is open to the atmosphere, and the supply of fuel liquid is maintained at a level above the lower end of the pipe 43, 10 which may be accomplished by several well known methods.

It will now be apparent that a substantially pure vapor, or a very dense vapor of the fuel is generated to fill the vacuum created by the 20 pump. The bottom of the supply pipe 43 is substantially sealed to the air by the liquid; and the vaporization of the fuel under the depressions created by the quick jerks of the pumps, which operate at high speeds, is promoted and sustained by the flow through the 25 small passages 42, the sudden expansion into the chamber of the reservoir 1, and the action in flowing into the perforations in the pipe 38.

An appreciable amount of air is contained 30 in all liquids, and especially in the highly volatile and unstable liquids used for fuel in internal combustion engines of the present type; and this contained air assists materially in maintaining the fuel in the vaporized condition until it is pumped into the power 35 cylinders of the engine.

In this manner the volume of the small quantity of the fuel in its liquid state, which is required in each charge, and which is difficult to handle and measure, is increased by 40 changing the fuel into a dense vapor. Then the volume is great enough to be conveniently handled by the available mechanical means, such as the relatively small piston pumps 45 shown, but still not so great that large pumps are required which would cause large inertia losses, unbalanced moments, and decrease the speed at which the engine could be operated. The passages 41 are provided in the bottom 50 reservoir head 37, leading from the bottom of the reservoir chambers into the passage 40 to drain any surplus liquid out of the chamber, which is disposed of through the pumps.

The single reservoir assures an even supply 55 of fuel to each pump, and the pumps are constructed to deliver a measured amount of the mixture to each cylinder. Control may be accomplished in any suitable manner, as by varying the strength of the mixture or by other methods which will be obvious to those skilled in this art.

The method of operation is best illustrated 60 by the diagram shown in Fig. 7, which gives the complete cycle of operations by the angular positions of the crank shaft. The point a

represents the top center; the line b, approximately fifty degrees ahead of the bottom center, the point at which the piston starts to uncover the exhaust ports; the line c, the opening of the air valve; the line e, the starting of the down-stroke of the fuel pump; d, the closure of the air valve and exhaust ports; and f, at ninety degrees from e—the completion of the pump stroke. Since a certain amount of pressure is required in the 70 pump to open the check valve 29 against the weight of the spring 127, the pump is effective for forcing fuel into the cylinder under compression during only a portion of its stroke, as between the angular engine crank 75 shaft positions g and h. The circle m represents the atmospheric pressure; p the combustion and expansion pressure; s, the pressure head on the scavenging air; and n, the compression pressures. The air valve is 80 opened about ten degrees after the exhaust to take advantage of the velocity head of the 85 gases flowing out of the exhaust ports, as well as for lowering the pressures of the gases below the pressure on the air. The air valve 90 may be closed with the exhaust or a few degrees ahead, and sufficient pressure is supplied to the scavenging air to blow several cylinder volumes of air down through the 95 cylinder.

It is now manifest that substantially the full period of the opening of the exhaust valves is available for the flow of the scavenging air, which is of great advantage in obtaining high speed. Considerable time 100 is also allowed for injecting the fuel, and the injection occurs during the beginning of the compression stroke before the higher pressures are reached, which reduced the amount of power required for injection, and also 105 causes a more thorough mixing before the fuel is ignited. This also reduces the tendency of the pumps to leak, since the pumps only act against a low resistance.

Having thus described my invention my 110 claims are as follows:

1. In an internal combustion engine, a plurality of cylinders, a vapor reservoir, means for generating a dense fuel vapor in the reservoir, a plurality of relatively small fuel pumps connected to said reservoir, said pumps being separately connected to the different cylinders.

2. In an internal combustion engine, a cylinder having a piston reciprocating therein, 120 means for opening the cylinder near the end of the expansion stroke, means for blowing several volumes of air through the cylinder while open, means for closing the cylinder at the beginning of the return stroke, a reservoir, means for generating a dense fuel vapor in the reservoir, a relatively small piston pump connected between the reservoir and the cylinder, and means for operating the pump to inject a measured amount of 130

the vapor into the cylinder at about the time the cylinder is closed.

- 5 3. In an internal combustion engine, a cylinder having a piston reciprocating therein, means for opening the cylinder near the end of the expansion stroke, means for blowing several volumes of air through the cylinder while the cylinder is open, means for closing the cylinder during the return stroke of the
- 10 10 piston, a reservoir, means for generating a dense fuel vapor in the reservoir, and means for pumping the vapor from the reservoir into the cylinder in measured quantities at about the time the cylinder is closed.
- 15 15 4. In an internal combustion engine, a closed reservoir, a liquid fuel receptacle, an intake pipe connected into the reservoir and having its lower end immersed in the liquid in the receptacle, and a piston pump for creating a vacuum in the chamber and discharging into one of the cylinders of the engine at the proper time to supply a measured quantity of the dense fuel vapor generated in the chamber by the depression into the engine cylinder.
- 20 20 5. In an internal combustion engine, a reservoir having a downwardly extending intake pipe, a liquid fuel receptacle, the lower end of the intake pipe being connected to the
- 25 30 receptacle so as to communicate a vacuum to the liquid, means for creating a vacuum in the reservoir, and means for transferring the dense fuel vapor generated in the reservoir into the engine cylinders.
